UNITED STATES PATENT OFFICE.

CHRISTOPHER J. LAWLESS, OF LINCOLN, NEBRASKA.

SILO-DOOR.

1,093,636.

Specification of Letters Patent. Patented Apr. 21, 1914.

Application filed November 19, 1913. Serial No. 801,902.

To all whom it may concern:

Be it known that I, CHRISTOPHER J. LAWLESS, a citizen of the United States, residing at Lincoln, in the county of Lancaster and 5 State of Nebraska, have invented a new and useful Silo-Door, of which the following is a specification.

The device forming the subject matter of 10 this application is a silo door, and one object of the invention is to provide a silo door, the hanger of which includes a portion constituting at once, the rung of a ladder, and 15 a means for supporting the door when the door is in an open position or in a closed position, the said portion of the hanger co-operating with the lower cross bar of the door frame, to effect this result.

Another object of the invention is to provide 20 novel means for assembling the ends of the hanger with the door frame.

Another object of the invention is to provide 25 a door hanger, the constituent elements of which may be separated readily, thereby permitting the use of one piece bearings upon the door and allowing the hangers to be lengthened or shortened to fit into different sized doorways.

It is within the scope of the invention to 30 improve generally and to enhance the utility of, devices of that type to which the present invention appertains.

With the above and other objects in view which will appear as the description proceeds, the invention resides in the combination 35 and arrangement of parts and in the details of construction hereinafter described and claimed, it being understood that changes in the precise embodiment of the invention herein disclosed can be made within 40 the scope of what is claimed without departing from the spirit of the invention.

In the accompanying drawings—Figure 1 shows the invention in front elevation, the door being in closed position; Fig. 2 is a 45 transverse section of the door and door frame; Fig. 3 is a fragmental vertical section of the upper cross bar of the door frame, the view depicting the supporting bracket in co-operation with the hanger; Fig. 4 is a 50 perspective view of the bracket; Fig. 5 is a horizontal section, showing the door in open position, the view depicting the manner in which the ladder forming portion of the hanger co-operates with the door frame to 55 support the door when the door is open; Fig. 6 is a fragmental perspective showing a

slight modification in the invention; and Fig. 7 is a perspective detail showing another slight modification in the invention.

In the accompanying drawings, a portion 60 of the door frame of a silo is shown, the frame comprising upright stiles 1 and cross bars 2 and 3, defining the door-way. The door is denoted by the numeral 35, and may be of any desired form. In the present instance, the door 35 is shown as comprising 65 upright cleats 4 and 5 united by a diagonal brace 6.

Mounted upon the cleat 4 are bearings 7, provided with transverse elongated slots 8, 70 receiving bolts or screws 9 which enter the cleat 4, the construction being such that the bearings 7 may be adjusted horizontally, and transversely of the door.

Securing elements 10 are mounted in the 75 diagonal brace 6 and in the upright cleat 4, the same receiving loops 11 formed in the ends of a horizontally disposed step 12.

Brackets 14 are secured to the cross bars 2 and 3, in vertical alinement, and adjacent 80 the longitudinal center of the door-way. These brackets as will be understood best from Fig. 4, are of S-shape. In the body 15 of each bracket 13 there are horizontally disposed elongated slots 16, adapted to receive 85 securing elements 16^a, which, engaging the cross bars 2 and 3, hold the brackets 14 in place for horizontal adjustment. Each bracket 14 comprises an outwardly extended horizontally disposed arm 17 and an inwardly 90 extended horizontally disposed arm 18, the arm 18 lying slightly below the lower face of the cross bar 2. In the arms 17 and 18 there are openings 19.

A hanger for the door 35 is provided, and 95 this hanger is a composite structure, the same comprising an L-shaped upper member 20 including a horizontally disposed arm 21 terminating in a downwardly extended finger 22. The finger 22 is received rotatably 100 in the opening 19 of the arm 18 of the bracket 14. The member 20 includes a vertical arm 23 which is journaled for rotation in the upper bearing 7. The extremity of the arm 23 is threaded as indicated at 24. 105 The hanger further includes an L-shaped lower member 25, the same comprising a horizontally disposed arm 26, offset to form a step 27 adapted to constitute one rung of a ladder. By the construction above outlined, an angle 28 is formed, having functions which will be set forth hereinafter, at 110

tention being directed especially to Fig. 5. The arm 26 forms an acute angle 26^a with one side portion of the step 27. The step 27 of the lower member of the hanger terminates in a downwardly extended finger 29 which is engaged in the opening 19 in the arm 17 of the lower bracket 14. The lower member of the hanger comprises a vertical arm 30 which is threaded as indicated at 10 31, in an opposite direction to the threading 24 of the arm 23, the threaded portions 31 and 24 receiving a turn-buckle 32.

If desired, an angle plate 33 may be secured to the lower cross bar 3, as shown in 15 Fig. 6. If desired, further, a flat plate 34 may be secured to the lower cross bar 3, as shown in Fig. 7.

Attention is especially directed to the fact that as clearly shown in Fig. 2, the horizontal arm 26 of the lower member 25 of the hanger, and more specifically the angle 26^a, rests upon the lower cross bar 3 when the door 35 is closed. This feature is of great importance, since the weight of a person standing upon the step 27, when the door is closed, is carried directly into the lower cross bar 3, thereby preventing the weight of a person ascending the silo, from being carried by the brackets 14, it being obvious, that a contingency of the sort just above mentioned would tend to alter the position of the door 35 with respect to the doorway of the silo.

The angle plate 33 shown in Fig. 6 may be employed to support the arm 26 of the 35 lower member of the hanger in the manner hereinbefore described, and is of use when the outer face of the door is substantially flush with the outer face of the door frame. The flat plate 34 shown in Fig. 7, exercises a 40 similar function, and its use will be clearly understood. The plates or supports 33 and 34 constitute a part of the door frame and will be so described in claiming this invention.

45 Referring particularly to Fig. 5, it will be noted that when the door is swung to open position, the angle 28 in the step, hereinbefore referred to, lies above the lower cross bar 3 and thus serves to uphold the 50 door when the door is open and swung to the left, reference being had to Fig. 1.

Owing to the fact that the hanger comprises the separable members 20 and 25, connected by the turn-buckle 32, the hanger 55 may be mounted readily in the bearings 7, it being possible to fashion each of these bearings 7 as a one-piece structure.

In order to remove the door 35, the door may be lifted slightly, and in this connec-

tion Fig. 6 may be examined with advantage. When the door is lifted, the finger 22 moves out of the opening 19 in the arm 18 of the hanger and the finger 29 moves out of the opening 19 in the arm 17 of the hanger. The door may then be slid to the right or to the left and subsequently be removed inwardly.

It is to be noted that the fingers 22 and 29 extend downwardly. Therefore, no matter how great a weight may be carried by the door, through the medium of the ladder forming steps or otherwise, the hanger will not be sprung out of engagement with the brackets 14.

Having thus described the invention, 75 what is claimed is:

1. In a silo, a frame; a hanger supported by the frame; and a door carried by the hanger; the hanger including a step, and a portion of the hanger being disposed directly above the lower portion of the frame to serve as a support for the door.

2. In a silo, a frame; a hanger supported by the frame; and a door carried by the hanger, the hanger including a part engaged across the lower portion of the frame when the door is open, thereby to support the door.

3. In a silo, a frame; a hanger supported by the frame; and a door carried by the hanger; the hanger including an arm offset to form a step and to define an angle in the step, the angle being disposed above the lower portion of the frame when the door is closed, thereby to support the door.

4. In a silo, a frame including a cross bar; a bracket secured to the cross bar and including vertically spaced arms; an upper hanger having one end journaled in one arm; a lower hanger having one end journaled in the other arm; and doors carried by the hangers.

5. In a silo, a frame; an S-shaped bracket secured to the frame and comprising an upper arm projecting away from the frame 105 and a lower arm projecting toward the frame, the lower arm being disposed below the lower face of the frame; a hanger having its ends journaled in the arms; and a door carried by the hanger.

In testimony that I claim the foregoing as my own, I have hereto affixed my signature in the presence of two witnesses.

CHRISTOPHER J. LAWLESS.
